UNITED STATES PATENT OFFICE.

GEORGE H. GIBSON, OF MONTCLAIR, NEW JERSEY.

FURNACE

1,417,374.

Specification of Letters Patent. Patented May 23, 1922.

Application filed November 17, 1917. Serial No. 202,478.

To all whom it may concern:

Be it known that I, GEORGE H. GIBSON, a citizen of the United States of America, and resident of Montclair, in the county of Essex and State of New Jersey, have invented a certain new and useful Improvement in Furnaces, of which the following is a true and exact description, reference being had to the accompanying drawings, which form 10 a part hereof.

My present invention relates to furnaces, and particularly to furnaces for heating steam generating boilers. The primary object of the invention is to provide novel and improved means for automatically proportioning the primary and secondary air supplies to a furnace burning solid fuel.

The various features of novelty which characterize my invention are pointed out 20 with particularity in the claims annexed hereto and forming a part of this specification. For a better understanding of the invention, however, and the advantages possessed by it reference should be had to the 25 accompanying drawings and descriptive matter in which I have illustrated and described a preferred embodiment of my invention.

Of the drawings:

30 Figure 1 is a diagrammatic elevation with parts broken away and in section of a steam generating plant.

Figure 2 is a partial section on the line 2—2 of Figure 1.

35 In the drawings; A represents the combustion chamber of the steam generating furnace proper, and A' the stack connection or outlet from the chamber A for products of combustion. The draft through the com-

40 bustion chamber A may be regulated by a damper A² in the connection A'. B represents the water tubes, and C the steam and water drum of the steam generating boiler heated by the hot gases sweeping through

45 the combustion chamber A. D represents a superheating coil in the pipe connection leading from the steam space of the drum C, to the high pressure inlet of a steam turbine E, and D' represents a superheating

50 coil located in the combustion chamber A and forming a part of the conduit leading from the exhaust of a high pressure stage of the turbine to the steam inlet of a lower pressure stage of the turbine.

55 The inlet to the combustion chamber A is connected to the gaseous outlet of a gas

producer chamber F. As shown, the connection is direct, the combustion chamber A comprising a portion which is located above, and in fact forms a continuation of the gas 60 producer chamber F. At the lower end of the gas producer is an ordinary solid fuel grate F', and F² represents a door through which solid fuel may be charged into the gas producer from time to time. G represents 65 the air supply connection to the ash pit F³ beneath the grate F'. The amount of air passing into the ash pit through the air supply inlet G is controlled by a steam jet issuing from the axially disposed nozzle H'. 70 The nozzle H' is supplied with steam from the boiler through the steam supply line H. The amount of steam discharged through the nozzle H' is controlled by the throttle valve K, which is automatically regulated 75 in a manner hereinafter described. The secondary air for burning the producer gas is supplied adjacent the inlet to the combustion chamber A through a conduit I, which is open to the atmosphere at I' and includes 80 a loop I² which projects into the smoke stack outlet A', so that the secondary air is pre-heated more or less by the waste products of combustion leaving the boiler furnace. The conduit I, in the construction shown, is 85 bifurcated with the forks I³ straddling the gas producer neck portion or conduit through which the producer gas is supplied to the combustion chamber A. Each fork I³ is open at its inner edge to the ends of the 90 hollow grate bars J, which extend across the chamber F and are formed with discharge orifices J' at their upper edges. These bars may be formed of cast iron in many cases, but where subjected to unduly 95 high temperatures should be made of more refractory material. Interposed between the fuel bed on the grate F', and the grate bars J are a group of inclined water tubes B' connected by the pipes B² into the steam 100 and water drum C.

The damper K is automatically adjusted and the proportion of primary air admitted at G and secondary air supplied through pipe I is thereby automatically regulated so 105 as to maintain a predetermined percentage of carbon dioxide in the products of combustion leaving the boiler furnace. The particular apparatus illustrated for accomplishing this result comprises means for continuously passing a small amount of the waste products of combustion from the smoke 110

stack connection A' to the chamber O' of a CO₂ absorbing device O. In the particular form of the device O illustrated the chamber O' is connected to a chamber O³ by a restricted port O². The chamber O³ is separated by a perforated wall O⁴ from a chamber O⁵. The latter communicates through a restricted orifice O⁷ with a chamber O⁶. The chamber O⁶ is provided with a discharge outlet O⁸, and a blast nozzle H² supplied with steam through the steam supply pipe H insures a suction out of the chamber O⁶ through the outlet O⁸. The chamber O³ is filled with a porous mass of some suitable CO₂ absorbing material such as caustic soda.

The chamber O⁶ is connected to the chamber O' by piping P, and is also connected to the upper end of a sealed receptacle R containing a body of liquid R' into which a pipe R², open at its upper end to the atmosphere, dips to a definite depth. The chamber O' is connected to the upper end of a receptacle Q containing a body of liquid Q' and provided with a pipe Q², which extends down into the liquid to a definite depth and is open at its upper end to the atmosphere. With the apparatus thus described, when the parts are suitably proportioned, they operate to maintain a definite vacuum in the chamber O⁶, and another definite, though somewhat lower vacuum, in the chamber O'. These vacuums correspond to the liquid heads in the receptacles R and Q above the lower ends of the pipes R² and Q², respectively. To accomplish this result the suction effect of the nozzle H² should be energetic enough at all times to draw some atmospheric air through the liquid R' in the receptacle R. Any increase within reasonable limits in the suction effect of the nozzle H² beyond that required to maintain a small flow of air through the pipe R' will not increase the vacuum in the chamber O⁶ appreciably, since any slight increase in this vacuum will largely increase the amount of air drawn into the chamber O⁶ from the receptacle R. The air thus admitted tends to diminish the vacuum in the chamber O⁶, and the vacuum in the chamber O' is thus maintained at approximately the predetermined value. The vacuum in the chamber O' is regulated in a similar manner by the liquid head above the bottom of the pipe Q². The existence of a constant pressure at the inlet side of the orifice O² and at the outlet side of the orifice O⁷ tends to maintain a constant flow through each of these orifices and a constant vacuum in the chamber O⁶, provided the percentage of CO₂ in the furnace gas remains constant.

If the CO₂ in the furnace waste gases diminishes a smaller percentage of the gas entering the chamber O⁶ is absorbed therein, and the vacuum in the chamber O⁶ is there-

by diminished. Conversely an increase in the percentage of CO₂ in the furnace waste gases results in an increased absorption of CO₂ in the chamber O⁶ and an increase in the vacuum in the chamber O⁵. The pressure in the chamber O⁵ is thus a measure of the percentage of CO₂ in the furnace waste gases. The vacuum in the chamber O⁵ is transmitted to the pressure chamber of the fluid pressure motor L. The flexible diaphragm of the motor L is so connected to the regulating valve K in the blast nozzle steam supply line that the damper K is opened, and more primary air supplied when the amount of CO₂ in the waste products falls below a predetermined percentage which it is desired to maintain, and when the amount of CO₂ rises above the predetermined percentage, the valve K is throttled to correspondingly reduce the primary air supplied to the ash pit F³ and thereby restore the desired percentage of CO₂ in the gaseous products of combustion. The percentage of CO₂ in the furnace gases which the apparatus tends to maintain may be varied by adjusting a counter balance weight L'. An arrangement of the type just described forms a novel and effective means for accurately proportioning the primary and secondary air supplied to a combustion furnace which is well adapted for use with many different kinds of furnaces.

The special arrangement of a gas producer and boiler furnace proper disclosed herein possesses the following important practical advantages in addition to the general advantages already referred to. The means employed for feeding the secondary air and admixing it with the producer gas arising from the fuel bed in the gas producer insures a very thorough admixture which is conducive to efficient combustion and possesses the advantage of reducing the required volume, and particularly, the height of the boiler combustion chamber proper. The absorption of heat by radiation from the fuel bed by the water tubes B' keeps down the temperature of the fuel bed and thereby reduces the amount of steam which it is necessary to supply with the primary air in order to avoid undue clinkering on the producer grate. The heat absorptive effect of the tubes B' also keeps down the temperature of the producer gas, and thereby reduces the temperature of the combustion chamber walls and the grate J. The manner in which the secondary air is admitted also contributes to this reduction in temperature, which is highly desirable, as it avoids the excessive deterioration experienced when such parts are subjected to somewhat higher temperatures.

While in accordance with the provisions of the statutes I have illustrated and described the best form of my invention now

known to me, it will be obvious to those skilled in the art that changes may be made in the form of the apparatus disclosed without departing from the spirit of the invention set forth in the appended claims, and that certain features of my invention may sometimes be used with advantage without a corresponding use of other features.

Having now described my invention, what I claim as new and desire to secure by Letters Patent, is:

- 10 1. In a furnace having primary and secondary air supplies, and means for adjusting the ratio of primary to secondary air, the combination therewith, of means automatically responsive to the amount of CO₂ in the waste gases for adjusting the previously mentioned means to maintain a predetermined percentage of CO₂ in the waste gases.
- 15 2. In a furnace having primary and secondary air supplies, means for varying the total amount of air supplied to thereby vary the combustion rate, and means for regulating the ratio of primary and secondary air supplied, the combination therewith of means automatically responsive to the amount of CO₂ in the waste gases for adjusting said ratio regulating means as required to maintain a predetermined percentage of CO₂ in the waste gases.
- 20 3. In a furnace having primary and sec-

ondary air supplies and means for regulating the ratio of primary to secondary air, the combination therewith of means automatically responsive to the chemical composition of the gaseous products of combustion issuing from the furnace for adjusting said ratio regulating means to maintain a predetermined composition of said gaseous products of combustion.

4. In a furnace having primary and secondary air supplies and means for regulating the ratio of primary to secondary air, the combination therewith of means automatically adjusting said ratio regulating means in response to the chemical composition of the gaseous products of combustion issuing from the furnace so as to minimize the variations in the chemical composition of said products dependent on said ratio.

5. In a furnace having primary and secondary air supplies and means for regulating the ratio of primary to secondary air, the combination therewith of means automatically responsive to the fractional content of the gaseous products of combustion issuing from the furnace formed by a particular constituent of said gases, for adjusting said ratio regulating means as required to maintain said fractional content approximately constant.

GEORGE H. GIBSON.
